Primary Examiner — Randall Gholson(74) *Attorney, Agent, or Firm* — Tutunjian and Bitetto, P.C.(57) **CLAIM**

The ornamental design for a set top box, as shown and described.

DESCRIPTION

FIG. 1 is a perspective view of the set top box showing our new design;

FIG. 2 is another perspective view thereof;

FIG. 3 is a front view thereof;

FIG. 4 is a left side view thereof;

FIG. 5 is rear view thereof;

FIG. 6 is a right side view thereof;

FIG. 7 is a top view thereof; and,

FIG. 8 is a bottom view thereof.

The broken lines depict portions of the set top box that form no part of the claimed design.
